No. 822,071.

PATENTED MAY 29, 1906.

A. F. & C. H. NORRIS.
LIFTER ROD HOLDER AND GUIDE.
APPLICATION FILED DEC. 31, 1904.

UNITED STATES PATENT OFFICE.

ALBERT F. NORRIS AND CLIFTON H. NORRIS, OF BOSTON, MASSACHUSETTS.

LIFTER-ROD HOLDER AND GUIDE.

No. 822,071.

Specification of Letters Patent.

Patented May 29, 1906.

Application filed December 31, 1904. Serial No. 239,250.

To all whom it may concern:

Be it known that we, ALBERT F. NORRIS and CLIFTON H. NORRIS, citizens of the United States, residing at Boston, in the 5 county of Suffolk and State of Massachusetts, have invented certain new and useful Improvements in Lifter-Rod Holders and Guides; and we do hereby declare the following to be a full, clear, and exact description 10 of the invention, such as will enable others skilled in the art to which it appertains to make and use the same.

This invention relates to improvements in musical instrument attachments, and more 15 particularly to lifter-rod holders and guides for pianos or the like.

Among the several objects in view is the adjustable supporting of a lifter-rod in a given position, while permitting free movement of said rod and preventing the production of sound by friction during such movement of the rod. In the art heretofore it has been common to provide a support having a straight smooth aperture lined with cloth, 20 the cloth being secured in position by glue. It is found that the glue hardens the cloth and produces a glazed surface thereof, against which the lifter-rod rubs in its movement, whereby a grating noise is produced. The 25 object of avoiding the production of such noise by the present invention is attained by the employment of means, as will be herein-after fully described, for supporting a cushion-lining within the aperture of a support- 30 ing-plate without the use of an adhesive, whereby the cushioning effect of the lining is maintained and the rod may move noiselessly past its support.

With this and further objects in view the 40 invention comprises certain novel constructions, combinations, and arrangements of parts, as will be hereinafter fully described and claimed.

In the accompanying drawings, Figure 1 45 represents a perspective view of a piano provided with a lifter-rod support embodying the features of the present invention, parts of the piano being broken away for illustrating interior structure. Fig. 2 represents a longitudinal vertical central section 50 taken through a support embodying the features of the present invention, parts being illustrated in elevation. Fig. 3 represents an inverted plan view of the same with the bracket omitted. Fig. 4 represents a detail view of the cushion-lining of the support in

its extended condition. Fig. 5 represents a view in side elevation of the present improved support, parts being broken away and the support being illustrated as applied 60 to a modified form of bracket. Fig. 6 represents a fragmentary longitudinal vertical section through a modified form of support.

Referring to the drawings by numerals, 1 indicates a piano-casing, and 2 a pedal-action of any ordinary type connected with and designed to operate a lifter-rod 3, said rod being designed for controlling the damper-rod, hammer-rail, muffler, or other mechanism designed to be operated by the pedals of 65 the piano. For the purpose of supporting and guiding the rod 3 we propose to provide a support comprising a plate or bar 4, apertured, preferably, at one end, as at 5, which aperture is lined by a suitable bushing 6, said 70 bar being provided at its opposite end with suitable securing means, hereinafter mentioned. The aperture 5 is, as will be observed, particularly in Fig. 2, formed with an 75 annular rib 7 midway of the aperture, and the walls of the aperture flare outwardly in both directions from said rib, so that at the point of the rib the aperture is restricted and is larger at all other points. Thus the aperture is formed with an angular wall which 80 may be provided with as great and as varied angles as desired, a portion of the bushing 6 thus necessarily overhanging a portion of the wall of said aperture. The bushing 6 consists of a strip of suitable cushioning material 85 cut preferably in the form of a substantially rectangular piece notched at its ends, as seen in Fig. 4, and rolled into a cylinder and placed in such condition within the aperture 5. The said cushion-lining 6 is after 90 having been positioned within the aperture pressed about the walls thereof in position for fitting snugly such walls, so that the rod 3 may be passed through the lining and be cushioned in its movement therethrough. 95 The flaring walls of the aperture 5 facilitate the movement of the rod 3 through the aperture at other angles than a right angle, as illustrated, and this is advantageous at times when the rod buckles or becomes tilted to 100 one side from any cause. It is to be noted that the lining 6 is simply positioned within the aperture without the use of adhesive or any securing material, and the presence of the rod 3 prevents said lining from leaving 105 the aperture, due to the fact that the rib or ridge 7 prevents longitudinal movement of

the lining, due to the flared condition of the ends thereof. Therefore it will be observed that by the employment of the rib 7 or some equivalent element the lining is sustained in 5 its proper position without the use of adhesive material.

At the opposite end of the bar 4 from that formed with the aperture 5, as above suggested, is arranged suitable securing means, which 10 consists of a roughened or serrated surface 8, and a screw or other attaching means 9, passed through the end of the bar 4 and designed to connect the same with a supporting means.

15 As seen in Fig. 2, the end of the bar 4 may be provided with a recess 10, adapted to receive a frusto-conical projection 11, carried by the end of a bracket 12, the screw 9 being passed through the bar 4 centrally of the recess 10 and engaging the frusto-conical projection 11 for locking the bar 4 to the bracket 12 when said bracket is employed, as seen in Fig. 2.

Where it is not desired to employ the 20 bracket 2, the bar 4 may be supported upon any suitable surface, as seen in Fig. 5, by the threading of the screw 9 into any convenient form of support and drawing the end of the bar 4 with its roughened or serrated surface 30 8 into engagement with the supporting-surface.

The screw 9 of course may be threaded down tightly enough to positively retain the bar 4 in the desired position, regardless of 35 whether the bracket 12 is employed or the bar connected with some other form of support, and when it is desired to adjust the bar 4 for adjusting the position of the lifter-rod 3 passed therethrough it is only necessary to 40 loosen the screw 9, swing the bar 4 pivotally upon said screw, and tighten the screw again.

Instead of forming the aperture 5 in the bar 4 in the manner disclosed in Fig. 2 an aperture may be formed, as seen at 5', in the 45 bar 4', the said aperture being lined with a suitable cushion 6'. The aperture 5' has its largest diameter at its center and tapers outwardly, so that, in common with the aperture 5, a part of the wall of the aperture overhangs 50 another part thereof and the cushion-lining therein must necessarily overhang a part of the wall of the aperture and be thereby supported in position without necessitating the use of an adhesive.

55 This application is a continuation of our former application, Serial No. 193,316, which was allowed and forfeited in order that this application might be filed.

Although we have illustrated a cylindrical 60 rod passing through the bushing 6, it is of course apparent that a square or other poly-sided rod, might be employed, and the cushion-lining 6 and the aperture carrying the same may be made to conform to the shape 65 of the rod.

Having thus fully described our invention, what we claim as new, and desire to secure by Letters Patent, is—

1. In a device of the class described, the combination with a piano or the like, and a 70 lifter-rod therefor, of a bar extending from one of the walls of the piano, and formed at its free end with an opening having an intermediate annular rib and a lining snugly fitting the wall of said opening and overhanging 75 the rib, said lining being designed to receive and guide said lifter-rod.

2. In a device of the class described, the combination with a casing, of a bracket secured thereto, a frustum extending from said bracket, a bar supported by said bracket and formed with a socket inclosing said frustum, an aperture being formed in said bar and restricted centrally and flaring outwardly to its ends, and a cushion-lining arranged within 85 and conforming to the contour of said aperture.

3. In a device of the class described, the combination with a piano, of a bar connected therewith and formed with an aperture, a 90 cushion-bushing mounted within said aperture, a rib projecting from the walls of the aperture into and partly filling the aperture and positioned centrally for being overhung by a portion of the bushing for maintaining 95 said bushing against removal therefrom, and a lifter passed through said opening.

4. In a device of the class described, the combination with a piano or the like, of a bar 100 extending from the walls thereof, and formed at its free end with an opening having an intermediate annular rib, a lining snugly fitting the walls of said opening and overhanging the rib, and a lifter-rod passed through said opening.

5. A device of the class described comprising a horizontally-movable bar formed with an aperture, means for securing said bar against movement, said aperture being provided with a ribbed surface, and a cushion-lining for the walls of said aperture.

6. In a device of the class described, the combination with a piano or the like, of a bar connected therewith and formed with an aperture having a double-beveled wall, a 115 lifter-rod passing therethrough, and a cushion-lining arranged within said aperture, one side of said lining conforming to the contour of the walls thereof and supported thereby.

7. In a device of the class described, the 120 combination with a piano, and a lifter-rod therefor, of a bar connected with the piano and formed with an aperture having a restricted portion intermediate its length and a cushion-lining for said aperture, part of said lining 125 overhanging the restricted portion of the aperture, said lifter-rod being surrounded and guided by said lining.

8. In a device of the class described, the combination with a piano, of a bar connected 130

therewith and formed with an aperture, the wall of said aperture being formed into an interior bead intermediate the length of the aperture and being flared in opposite direction from the bead, a lining snugly fitting the wall of said aperture and overhanging said bead for being sustained in position, and a lifter-rod passed through the aperture.

9. In a device of the class described, the combination with a piano, of a bar connected therewith, and formed with an oppositely-

flared aperture, a cushion-lining snugly fitting the wall of said aperture, and a lifter-rod passed through the aperture.

In testimony whereof we affix our signatures in presence of two witnesses:

ALBERT F. NORRIS.
CLIFTON H. NORRIS.
